CLAIM

The ornamental design for a handset telephone and stand for vehicles, substantially as shown and described.

DESCRIPTION

FIG. 1 is a front elevational view of a handset telephone and stand for vehicles; showing my new design in cradled relationship;

FIG. 2 is a rear elevational view thereof;

FIGS. 3 and 4 are respectively right and left side elevational views thereof;

FIGS. 5 and 6 are respectively top and bottom plan views thereof;

FIG. 7 is a sectional view taken on line VII—VII in FIG. 1 with interior construction omitted;

FIG. 8 is a left side, top and front perspective view thereof; and

FIG. 9 is a bracketed right side, bottom, and front perspective view of the handset telephone shown alone, and a left side, top, and front perspective view of the stand shown alone.

The abbreviated showing of a cord in sundry figures is for ease of illustration.
